US0D1059504S

(12) **United States Design Patent** (10) Patent No.: **US D1,059,504 S**
(45) Date of Patent: ** Jan. 28, 2025

(54) **FIGURINE TOY**

(71) Applicant: **DAMAXIMUM Sàrl**, Geneva (CH)

(72) Inventors: **Marcus Veith**, Geneva (CH); **Danilo Ceccarini**, Prégny-Chambésy (CH)

(**) Term: **15 Years**

(21) Appl. No.: **35/519,125**

(22) Filed: **Nov. 10, 2023**

(80) **Hague Agreement Data**

Int. Filing Date: **Nov. 10, 2023**

Int. Reg. No.: **DM/233205**

Int. Reg. Date: **Nov. 10, 2023**

Int. Reg. Pub. Date: **Nov. 24, 2023**
